[57] CLAIM

The ornamental design for a simulative toy tape measure, as shown and described.

DESCRIPTION

FIG. 1 is a front elevational view of a simulative toy tape measure showing my new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof; and

FIG. 7 is a perspective view thereof with a portion of the tape member extended.
